SPOON OR OTHER ARTICLE OF TABLEWARE

Harold K. Mottus, Alberta, Canada

Application May 1, 1952, Serial No. 19,548

Term of patent 7 years

(Cl. D54—12)

To all whom it may concern:

Be it known that I, Harold K. Mottus, a citizen of Canada, residing in the county of Battle Lake, Alberta, Canada, have invented a new, original, and ornamental Design for a Spoon or Other Article of Tableware, of which the following is a specification, reference being had to the accompanying drawing, forming a part thereof.

Fig. 1 is a front elevational view of a spoon showing the essential features of my new design in full lines;

Fig. 2 is a side elevational view of Fig. 1;

Fig. 3 is a back elevational view of Fig. 1.

The design is intended for use on sets comprising spoons, forks, knives and similar articles of tableware.

I claim:

The ornamental design for a spoon or other article of tableware, substantially as shown and described.

HAROLD K. MOTTUS.
